CLAIM

The ornamental design for a motorcycle lift, as shown and described.

DESCRIPTION

FIG. 1 is a right front perspective view of a motorcycle lift, according to the present invention;

FIG. 2 is a front elevation view of the motorcycle lift of FIG. 1;

FIG. 3 is a rear elevation view of the motorcycle lift of FIG. 1;

FIG. 4 is a left side elevation view of the motorcycle lift of FIG. 1;

FIG. 5 is a right side elevation view of the motorcycle lift of FIG. 1;

FIG. 6 is a top view of the motorcycle lift of FIG. 1; and, FIG. 7 is a bottom view of the motorcycle lift of FIG. 1. Broken lines, where present, illustrate portions of the motorcycle lift that form no part of the claimed design.
